UNITED STATES PATENT OFFICE.

LINN BOYD BENTON, OF MILWAUKEE, WISCONSIN.

DESIGN FOR A FONT OF PRINTING-TYPE.

SPECIFICATION forming part of Design No. 20,120, dated August 26, 1890.

Application filed July 31, 1888. Serial No. 281,563. Term of patent 7 years.

To all whom it may concern:

Be it known that I, LINN BOYD BENTON, of Milwaukee, in the county of Milwaukee and State of Wisconsin, have invented a certain 5 new and original Design for Printing-Type; and I do hereby declare that the following is a full, clear, and exact description of the invention, which will enable others skilled in the art to which it pertains to make and use 10 the same, reference being had to the accompanying printed impression, which forms a part of this specification.

The nature and distinguishing features of 15 my design, which are carried out both in the upper and the lower case characters, consist in a bold or black face of nearly uniform width, except at the terminals of the letters, and in giving the characters scroll or leaf shaped terminations.

20 Generally the main terminals of the characters consist of two points formed by the intersection of three curved lines; and to give variety to the font and a graceful sweep to the terminals of the different characters the intersecting curved lines forming the points of 25 the terminals are variously disposed, as seen in the two lower terminals of capitals A, H, M, N, &c., and in the upper terminals of the

capitals K, N, U, V, W, X, and Y. In the lower-case h, m, and n one of the lower terminals is extended below the line in a double turn, ending in a single point. 30

I provide the font with two styles of capital E and two styles of lower-case s. The font is also provided with figures, all of which exhibit 35 the characteristic terminals except 8 and 0.

The design differs also in other particulars, clearly distinguishable to the eye of the ordinary observer, from all other designs within my knowledge. 40

Having thus described my invention, what I claim as new, and desire to secure by Letters Patent, is—

A design for a font of printing-type, in which the characters have a heavy face throughout 45 and the stems terminate in two divergent points formed by the intersection of three curved lines, the end curve being re-entrant, substantially as shown and described.

In testimony that I claim the foregoing as 50 my own I affix my signature in presence of two witnesses.

LINN BOYD BENTON.
